APPARATUS FOR DRAWING A BRANCHED
FILAMENT

Frederick Scragg and Alexander Albert Chubb, Macclesfield, England, assignors to Ernest Scragg & Sons Limited, Macclesfield, England

Original application Sept. 6, 1962, Ser. No. 222,993. Divided and this application Dec. 22, 1964, Ser. No. 420,312

Claims priority, application Great Britain, Dec. 6, 1960, 41,955/60; Sept. 6, 1961, 32,008/61
8 Claims. (Cl. 18—1)

The present invention relates to branched textile filaments and a process and apparatus used during the manufacture of such filaments.

This application is a division of our copending application Serial No. 222,993, filed September 6, 1962, entitled "Yarns and the Manufacture Thereof," which application Serial No. 222,993, in turn, is a continuation-in-part of our copending application Serial No. 157,080, filed December 5, 1961, entitled "Yarn and Process and Apparatus for Manufacturing the Same."

As is disclosed in the above application it is possible to manufacture thermoplastic yarns which have branches from the filamentary portions of the yarns. The filament is produced from synthetic thermoplastic material having a highly polymerized molecular structure, and the filament is distinguished by having a series of side projections or branches which are produced in a manner described in the above application. It is known that in order to provide a filament with a structure enabling it to be used as a textile yarn it must be drawn so as to orient its molecular structure and increase its strength.

It is accordingly a primary object of the present invention to provide a branched filament of the above type which has both the filamentary portion thereof as well as the branches which project therefrom oriented with respect to their molecular structure and of an increased strength as compared to the untreated yarn, and the objects of the present invention also include the process and apparatus for manufacturing this yarn.

It is in particular an object of the present invention to provide a process and apparatus which will draw the branched filament not only at its elongated filamentary portion from which the branches project but also at the branches themselves, so that in this way as a result of the drawing, the drawn yarn has at its filamentary portion a lesser diameter than the diameter of the untreated yarn and also the branches are of a smaller diameter than the branches of the undrawn yarn, and in this way the rigidity of both the filamentary portion of the yarn as well as the branches thereof is increased.

Also, the objects of the present invention include a process wherein the filament is initially placed in a condition which will promote the proper drawing thereof both at its branches and at its filamentary portion; as well as a process which after the drawing of the yarn will restore it to the condition where the branches project from the filamentary portion of the yarn.

With these objects in view the invention includes, in a process for manufacturing a branched thermoplastic filament, the steps of bending the branches of the thermoplastic filament inwardly toward the filamentary portion thereof on which the branches project, and then drawing the filament both at its filamentary portion as well as at its branches, preferably with the simultaneous application of heat to the filament, so that in this way the filament is drawn both at its filamentary portion and at its branches to improve its molecular structure as well as to increase its strength.

The apparatus of the invention include a condenser

2

for bending the branches inwardly toward the filamentary portion, as well as two pairs of drawing rolls providing a drawing assembly and means for heating the yarn as is drawn, and in addition there is preferably provided a brushing means for brushing the branches up from the filamentary portion of the yarn after the drawing thereof. The yarn can be treated in accordance with the invention either separately or preferably in relatively large numbers of filaments which are treated simultaneously, the filaments being combined as, for example, by means of a low twist either before or after drawing so as to form a composite yarn. Branches which extend to too great a length from the yarn may be burnt or cut-off to a predetermined length.

15 The novel features which are considered as characteristic for the invention are set forth in particular in the appended claims. The invention itself, however, both as to its construction and its method of operation together with additional objects and advantages thereof, will be best understood from the following description of specific embodiments when read in connection with the accompanying drawings, in which:

20 FIG. 1 is a schematic side elevation of one embodiment of the apparatus of the invention used to practice the process of the invention in order to manufacture the yarn of the invention;

25 FIG. 2 is a side elevation of an embodiment similar to FIG. 1 but including more detail with respect to the particular components;

30 FIG. 3 is a schematic illustration of an untreated filament before it has been drawn according to the invention;

35 FIG. 4 is a schematic illustration of the filament of FIG. 3 after it has been drawn; and

FIG. 5 shows a schematic plan view of the manner in which the drawing rolls act on the filament, the line along which the drawing rolls engage the filament being shown in a dot-dash line in FIG. 5.

Referring now to FIG. 1, there is shown therein a roll 11 of untreated filament 12, this filament passing through a known funnel-shaped condenser or, more clearly expressed, deflector 26 so as to have the branches bent inwardly toward the axis of the filament along which the filamentary portion thereof extends, the branches projecting from the filamentary portion. Thus, with the filament 12 moving to the right, as viewed in FIG. 1, the free ends of the branches will be directed toward the left, as viewed in FIG. 1, and a first pair of drawing rolls 13 and 14 receive the filament 12 from the condenser, one or both of the rolls 13 and 14 being heated so that the filament will be heated.

The filament is received from the first pair of drawing rolls 13, 14 by a second pair of drawing rolls 15, 16 which rotate at a speed faster than the rolls 13, 14 so that the filament is drawn as it passes along the path extending between the pairs of drawing rolls.

The structure is shown in FIG. 2 where the filament moves to the right, the supply roll 11 being shown at the left, and as is indicated in FIG. 2 before the filament reaches the drawing rolls 13, 14 it passes between a pair of rolls 17, 18 which absorb any tension differences experienced during unwinding of the untreated filament 12 from the roll 11 and which provide a uniform rate of feed of the filament to the first pair of drawing rolls 13, 14. The rolls 14 and 18 are driven from a common motor 19 through an endless belt 20 which engages pulleys driven by the motor as well as coaxial with the rolls 14 and 18 connected thereto, and a heating means is shown diagrammatically in FIG. 2 connected operatively with the lower roller 14 of the first pair of drafting rolls 13, 14. For example, the roll 14 may be hollow and may have in its interior an electrical heating element con-

nected electrically with slip rings located at an end wall, or at both end walls, of the roll 14 and engaging brushes which are connected electrically to a source of current which places the heating elements in the interior of the roll in an electrical circuit which will cause them to become heated and to heat the roll 14 so that in this way the yarn itself will be heated as it passes between the rolls 13, 14.

In order to insure that the filament is securely gripped between the second pair of rolls 15, 16 a circumferentially grooved idler roll 21 permits the filament to be wrapped twice around the roll 15, the filament passing around the idler 21, before passing around a guide member 22 so as to be finally collected on the package 23 which takes up the filament in a known manner by frictionally engaging, through its own weight, the peripheral surface of a driving roll 24, as indicated in FIG. 2.

The filament 12 is indicated in FIG. 3 before it is treated according to the invention and as may be seen the branches of the filament extend in such a direction that when the filament is between the rolls 13, 14 and 15, 16, the free ends of the branches of the filament are directed toward the rolls 13, 14. As may be seen from FIG. 5, the rolls 13, 14 grip the filament as it moves to the right, as viewed in FIG. 5, along the dot-dash line indicated in FIG. 5 with the diameter of the filamentary portion as well as the branch becoming smaller as shown on an exaggerated scale in FIG. 5, as the yarn advances to the right, as viewed in FIG. 5, beyond the line where the yarn is gripped between the rolls 13, 14. Of course, it is the faster speed of the rolls 15, 16 which draws the yarn so that it will become elongated at the line along which it is gripped by the first pair of drawing rolls, as indicated in FIG. 5.

The resulting filament according to the invention is illustrated in FIG. 4 which, as compared with FIG. 3 clearly indicates how the filament has had its diameter reduced both along its filamentary portion as well as along the branches extending from the filamentary portions, and it will be noted from a comparison of FIGS. 3 and 4, how much longer the branches are in FIG. 4 than in FIG. 3. Any suitable rotary brushes or the like may be applied to the filament in order to brush up the branches thereof subsequent to the drawing operation.

The bending of the branches by the condenser bends them inwardly toward the filamentary portion of the filament so that the branches shown in FIG. 3 will turn in a substantially counterclockwise direction with respect to the junctions between these branches and the filamentary portion of the filament during the inward bending of the branches by the condenser. As is apparent from the above description, the yarn of the invention manufactured according to the process and apparatus of the invention can be continuously treated so as to produce a branched filamentary structure to be used in connection with textile materials wherein the filaments are fully drawn so that the maximum strength of the material is achieved both in the filamentary portion thereof as well as in its branches, and the material may be dyed either before or after the drawing operations, or the dye may be incorporated in the melt from which the filaments are formed.

It will be understood that each of the elements described above or two or more together, may also find a useful application in other types of textiles differing from the types described above.

While the invention has been illustrated and described as embodied in thermoplastic filaments, it is not intended to be limited to the details shown, since various modifications and structural changes may be made without departing in any way from the spirit of the present invention.

Without further analysis the foregoing will so fully reveal the gist of the present invention that others can by

applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

Thus, it is not necessary to use a condenser if the filament is made in a particular manner. If the branches are produced in such a manner as to project substantially at right angles to the line of the filament, then some bending device is of course necessary. However, it is just as easy to cast or extrude a shape in which the branches lie substantially parallel with the main filament at an angle substantially as shown in FIGS. 4 and 5, in which case the condenser is unnecessary.

What is claimed and desired to be secured by Letters Patent is:

1. In an apparatus for manufacturing branched textile filaments from thermoplastic material in which an untreated filament travels in a given direction, in combination, means for bending the branches of an untreated filament transversely of said given direction and toward the filamentary portion from which the branches extend; a first pair of drawing rolls for receiving the filament and the branches after the latter have been bent toward the filament in said means; and a second pair of drawing rolls receiving the filament from the first pair of drawing rolls and rotating at a speed faster than the first pair of drawing rolls and rotating at a speed faster than the first pair of drawing rolls so that the filament will be drawn both at its filamentary portion as well as at its branches.

2. In an apparatus for manufacturing from thermoplastic material textile filaments comprising a continuous trunk and a plurality of spaced branches extending laterally therefrom and having free ends, in combination, means for deflecting said free ends of said branches in the direction toward said trunk; first engaging means for engaging both said trunk and said branches, the latter at a location spaced from their juncture with said trunk; and second engaging means spaced from said first engaging means for receiving said trunk and branches from said first engaging means, and for exerting axial pull on the trunk whereby both said trunk and the respective branches engaged by said first engaging means are elongated.

3. In an apparatus for manufacturing from thermoplastic material textile filaments, each filament comprising a continuous trunk and a plurality of spaced branches extending laterally therefrom and having respective free ends, in combination, means for gradually deflecting said free ends of said branches toward said trunk; a first pair of cooperating rotating drawing rolls for engaging said trunk and said branches, the latter respectively at a location adjacent their free ends; and a second pair of cooperating drawing rolls rotating faster than said first pair and spaced therefrom, said second pair of drawing rolls engaging said filament and stretching said trunk and said branches in axial direction of the trunk.

4. In an apparatus for manufacturing from thermoplastic material textile filaments, each filament travelling in a given axial direction of the filament through the apparatus and comprising a continuous trunk and a plurality of spaced branches extending laterally therefrom and having respective free ends, the combination of means for gradually deflecting said free ends of said branches transversely of the direction of travel and toward said trunk; a first pair of cooperating rotating drawing rolls for engaging said trunk and said branches, the latter respectively at a location adjacent their free ends upon said deflection having been completed; and a second pair of cooperating drawing rolls rotating faster than said first pair and spaced therefrom, said second pair of drawing rolls engaging said filament and stretching

said trunk and said branches in axial direction of the trunk.

5. In an apparatus for manufacturing textile filaments from thermoplastic material, with each of said filaments comprising a continuous trunk travelling in a given direction and being formed with a plurality of spaced branches extending laterally and having respective free ends, the combination of deflector means for gradually deflecting said free ends of said branches transversely of the direction of travel and toward said trunk; a first pair of cooperating rotating drawing rolls for engaging said trunk, and simultaneously engaging the deflected branches adjacent their respective free ends; and a second pair of cooperating drawing rolls spaced from said first pair and engaging said filament, said second pair of drawing rolls rotating at a higher speed than said first pair whereby said trunk and said branches are stretched.

6. In an apparatus for manufacturing textile filaments from thermoplastic material, with each of said filaments comprising a continuous trunk travelling in a given direction and being formed with a plurality of spaced branches extending laterally and having respective free ends, the combination of funnel-shaped deflector means having a wide inlet opening and a narrow outlet opening spaced therefrom in the direction of travel of said filament, said deflector means having an inner diameter gradually tapering toward said outlet opening for gradually deflecting said free ends of said branches toward said trunk as said filament travels through said deflector means; a first pair of cooperating rotating drawing rolls for engaging said trunk, and simultaneously engaging the deflected branches adjacent their respective free ends; and a second pair of cooperating drawing rolls spaced from said first pair and engaging said filament, said second pair of drawing rolls rotating at a higher speed than said first pair whereby said trunk and said branches are stretched.

7. In an apparatus for manufacturing textile filaments from thermoplastic material, with each of said filaments comprising a continuous trunk travelling in a given direction and being formed with a plurality of spaced branches extending laterally and having respective free ends, the combination of funnel-shaped deflector means having a wide inlet opening and a narrow outlet opening spaced therefrom in the direction of travel of said filament, said deflector means having an inner diameter grad-

ually tapering toward said outlet opening for gradually deflecting said free ends of said branches toward said trunk as said filament travels through said deflector means; a first pair of cooperating rotating drawing rolls for engaging said trunk, and simultaneously engaging the deflected branches adjacent their respective free ends; and a second pair of cooperating drawing rolls spaced from said first pair by a distance greater than the length of the respective branches and engaging said filament, said second pair of drawing rolls rotating at a higher speed than said first pair whereby said trunk and said branches are stretched.

8. In an apparatus for manufacturing textile filaments from thermoplastic material, with each of said filaments comprising a continuous trunk travelling in a given direction and being formed with a plurality of spaced branches extending laterally and having respective free ends, the combination of funnel-shaped deflector means having a wide inlet opening and a narrow outlet opening spaced therefrom in the direction of travel of said filament, said deflector means having an inner diameter gradually tapering toward said outlet opening for gradually deflecting said free ends of said branches toward said trunk as said filament travels through said deflector means; a first pair of cooperating rotating drawing rolls for engaging said trunk, and simultaneously engaging the deflected branches adjacent their respective free ends; and a second pair of cooperating drawing rolls spaced from said first pair and engaging said filament, said second pair of drawing rolls rotating at a higher speed than said first pair whereby said trunk and said branches are stretched; and heating means at said first pair of rolls for heating said filament simultaneously with the stretching thereof.
